(57) **CLAIM**

The ornamental design for a dispenser for cleanser, as shown and described.

DESCRIPTION

FIG. 1 is a front elevation view of a dispenser for cleanser showing my new design;

FIG. 2 is a rear elevation view thereof;

FIG. 3 is a right side elevation view thereof;

FIG. 4 is a left side elevation view thereof;

FIG. 5 is a top view thereof;

FIG. 6 is a bottom view thereof; and

FIG. 7 is an upper left front perspective view thereof.

FIG. 8 is a front elevation view of a dispenser for cleanser showing my new design in accordance with a second embodiment of the present invention;

FIG. 9 is a rear elevation view thereof;

FIG. 10 is a right side elevation view thereof;

FIG. 11 is a left side elevation view thereof;

FIG. 12 is a top view thereof;

FIG. 13 is a bottom view thereof; and,

FIG. 14 is a lower front right perspective view thereof.
